UNITED STATES PATENT OFFICE

LE ROY COPELIN, OF JACKSONVILLE, FLORIDA

SELF LEVELING CLOCK ESCAPEMENT VERGE ROD

Application filed April 2, 1929. Serial No. 351,949.

This invention relates to improvements in escapement verges for pendulum clocks and has for its primary object to provide, in a manner as hereinafter set forth, an improved 5 verge structure by means of which a self leveling of the escapement will take place when the clock is out of level.

Further objects of the invention are to provide a verge attachment which may be used 10 as part of the original equipment in the manufacture of clocks or which can be applied as repair or replacement parts in substitution for the old types; to provide a verge or verge rod that requires no change in the pallets or 15 designs of escapement now used in clocks but which can be applied to any of them; to provide an attachment on the verge rod whereby the escapement automatically and instantly finds its own level so that the clock will beat 20 properly regardless of the inclination of the surface upon which it is placed; to provide a structure which will act as a governor, gently but surely checking any abnormal swinging of the pendulum, the checking effect diminishing 25 in accord with the diminishing swing of the pendulum as the clock runs down thereby eliminating the objectionable fault of the clock running fast on full winding and slow on short or incomplete winding; to provide 30 a structure whereby the escape wheel and pallets are relieved of the burden of holding the verge in a locking position and the detrimental effects therein; and to provide a structure which can be stamped out free from 35 springs, friction, rivets, screws and adjustments and the objections thereto.

The invention will be best understood from a consideration of the following detailed description taken in connection with the accompanying drawings forming a part of the present invention with the understanding, however, that the invention is not confined to any strict conformity with the showing of the drawings, but may be changed or modified so long as such changes or modifications mark no material departure from the salient features of the invention as expressed in the appended claims.

In the drawings:—

Figure 1 is a view in rear elevation of a

portion of a clock works mechanism, showing the pendulum and the device embodying the present invention associated therewith:

Figure 2 is a view showing the pendulum of Figure 1 in side elevation and the verge 55 rod in longitudinal section;

Figure 3 is a sectional view taken upon the line 3—3 of Figure 1;

Figure 4 is a detailed perspective view of a modified form of the structure shown in Figures 1 to 3.

Referring to the drawings in detail, the numeral 1 indicates the back plate of a clock mechanism showing through the opening 2 in the upper portion thereof, a part of an escapement wheel 3, and the usual verge pallet 4 which permits the escapement wheel to escape in the usual well known manner. This pallet 4 is mounted upon a shaft 5 which is mounted at one end in the plate 1, in the manner shown.

The improved verge rod embodying the present invention is indicated by the numeral 6, the upper end thereof being offset as indicated at 7 for extension through the aperture 2 into the space between the clock mechanism walls, which end is secured to and carried by the verge pallet shaft 5, as shown, the main portion of the rod depending over the outer face of the mechanism plate 1.

The plate 1 carries the usual pair of spaced guard pins 8 which project therefrom in parallel relation and at opposite sides of the verge rod 6. The lower end of the verge rod 6 is formed to provide the oppositely directed lateral arms 9 from the free end of each of which there extends outwardly from the plate or wall 1 of the clock mechanism, the plate carrying arms 10, each of which is provided with a longitudinally extending slot 11. As shown these arms are spaced apart and are substantially parallel and there is supported between the arms 10, a relatively long flat plate 12, the ends of which extend through the slots 11 and are lightly held therein by engagement with the lower edges of the slot so that while the plate may be shifted in the slots 11 laterally of the arms 10, some slight resistance is offered to

such shifting, the weight of the plate determining the amount of resistance.

The plate 12 has formed therethrough intermediate its ends, the transverse slot 13 and through this slot extends the pendulum wire 14. The upper end of the pendulum wire carries the usual flat spring 14' which is removably secured to the peg 15 carried by the plate, in the usual manner. The lower end of the pendulum wire is formed to provide the usual hook 16 over which the eye 17 of the arm carried by the pendulum weight 18 engages.

From the foregoing description taken in association with the accompanying drawings, it will be readily understood that when a clock containing a movement so equipped, is placed on a surface either level or otherwise the following action will take place when the pendulum is given its initial start.

By means of the resistance caused by the weight of the plate 12 and its sliding contact in slot 13 on the carrying arm 10, the verge rod assembly will move with the pendulum rod 14, by means of contact at slot 13 until verge rod 6 stops in locking position on one of the guards or banking pins 8, said verge rod remaining in that locked position while the relatively light plate 12 shifts with the pendulum rod 14 while the pendulum ball 18 is completing its swing in that direction.

Therefore, the clock escapement is now adjusted ready to receive the impulse of the escape wheel 3 on pallet 4 which is likewise delivered to the pendulum rod 14 by means of the plate 12 which is of sufficient weight to deliver said impulse without shifting, but when the verge rod stops at the other guard pin 8 the plate likewise shifts with the pendulum rod while the pendulum ball completes its oscillation.

Therefore, the plate 12 shifts with each oscillation of the pendulum, thereby finding its beat and center of gravity continuously, thus making it responsive to any change of position of the clock however slight, gradual or abrupt.

In Figure 4 there is shown a modification of the structure in Figures 1 to 3, this modification being an adaptation of the invention to a replacement part which may be attached to verge rods of the usual type where it is desired to convert them to a structure in accordance with the present invention.

This modified form which is indicated as a whole by the numeral 19, comprises a short plate or bar 20 having rearwardly extending ears at the upper and lower end and at each side, as indicated at 21, which ears are designed to be bent back over the old type of verge rod to secure the present modified form in position.

At the lower end of the rod 20 a pair of lateral arms 22 is formed, each of which has extending forwardly therefrom an arm 23

longitudinally slotted as indicated at 24 for the reception of the friction plate 25 centrally, transversely apertured, as indicated at 26, like the plate 12.

These replacement units, as will be readily understood, may be easily and quickly secured upon a verge rod of any type whether the same be stamped of metal or made of wire, and if an offset verge be used the attachment may be offset correspondingly.

Having thus described my invention, what I claim is:—

1. A self leveling clock escapement verge rod, comprising a rod body, a clock pendulum wire engaging element, and supporting arms carried by the body and adapted to shiftably support the element.

2. A self leveling clock escapement verge rod, comprising a rod body, spaced substantially right angularly extending arms carried by said body, and a plate shiftably carried by the arms, said plate having an opening intermediate the ends thereof for receiving a clock pendulum wire, said opening being positioned between said arms.

3. A self leveling clock escapement verge rod, comprising a rod body designed to be secured at one end to a pallet shaft, a pair of arms carried by and projecting from the other end of the rod in spaced substantially parallel relation with one another, a plate member formed to loosely receive a clock pendulum wire intermediate its ends, and means whereby said arms shiftably engage said plate at opposite sides of the wire engaging means to support the plate from the lower end of the verge rod.

4. A self leveling clock escapement verge rod, comprising a rod body, a pair of laterally extending arms formed at one end of the body, a pair of forwardly extending longitudinally slotted arms each carried by and at the outer end of a first mentioned arm, and a plate member having its ends extended through said slotted arms for support therebetween and having a slot intermediate its ends between the slotted arms for the reception of a pendulum wire.

5. A self leveling clock escapement device, comprising a body having an upstanding portion designed to be detachably secured to a verge rod, arms projecting from the upstanding portion, and a member carried by said arms designed to receive a clock pendulum wire, said member being shiftable on and transversely of the arms to change the center of gravity of the attached verge rod.

6. A self leveling clock escapement verge rod, carrying an elongated shiftable member disposed and shiftable bodily in a line substantially at right angles thereto and designed to receive a pendulum wire, said member when shifted by the pendulum wire changing the center of gravity of the verge rod.

7. In a self leveling clock escapement verge

rod, a rod body, a clock pendulum wire engaging member, and means for shiftably supporting said member from the rod for movement bodily in a straight line transversely thereof, whereby changes in the relative positions of the rod and wire may take place without affecting the clock escapement.

5 In testimony whereof I hereunto affix my signature.
